J. J. STEWART.

BALING PRESS.

APPLICATION FILED OCT. 31, 1916.

1,276,986.

Patented Aug. 27, 1918.

UNITED STATES PATENT OFFICE.

JESSE J. STEWART, OF YALE, ARKANSAS.

BALING-PRESS.

1,276,986.

Specification of Letters Patent. Patented Aug. 27, 1918.

Application filed October 31, 1916. Serial No. 128,749.

To all whom it may concern:

Be it known that I, JESSE J. STEWART, a citizen of the United States, residing at Yale, in the county of Johnson and State of 5 Arkansas, have invented certain new and useful Improvements in Baling-Presses, of which the following is a specification.

An object of my present invention is to provide a new and improved baling press 10 of a type that may be manually operated, and wherein the plunger is mounted in a manner whereby the greatest possible leverage may be obtained thereon during the baling operation so as to compensate, to 15 some extent for the resistance offered by the material that is being baled, and to permit the same to be freely moved by the operator.

Another object of my invention is to provide improved means for actuating the 20 plunger so that the same may be made to exert a very great pressure upon the material that is being baled, even more so than the pressure applied to the operating lever; and improved means to act in conjunction 25 with the said operating means to assure the resetting of the plunger after the termination of the pressing stroke.

A further object of my invention is to provide improved means for retaining the 30 plunger firmly in engagement with the material that is being baled, either during the baling operation, should the operator see fit to do so, or after the final pressing stroke thereof, so as to relieve the operator from 35 duty at the operating lever in order that he may effect the tying of the bale or the removal of the same from the press.

A yet further object of my invention is to so mount the entire press that it may be 40 easily and quickly moved from place to place, such as from one field to another when baling hay, alfalfa, or the like.

A still further object of my invention is to so arrange the body of the press that the 45 finished bale may be easily and quickly removed therefrom, and to provide suitable reinforcement therefor to compensate for the strain exerted during the baling operation.

50 Another object is to provide an improved baling press of the type in question that is extremely simple in construction, strong and durable, and highly practical from both the

standpoint of the manufacturer and the 55 standpoint of the user; and which, it is believed, may be manufactured at a comparatively low cost.

Various other objects and advantages will 60 become apparent in the following description.

These objects are accomplished by means 65 shown in their preferred form in the accompanying drawings, described in the following specification and then more specifically pointed out in the appended claims.

In the accompanying drawings wherein 70 like characters designate like parts throughout the several views:

Figure 1 is a view in side elevation showing my invention as in its preferred embodiment. The body of the press, in this figure, is shown slightly broken away to disclose the plunger construction more clearly.

Fig. 2 is a view in cross section taken on line 2—2 of Fig. 1 looking in the direction indicated by the arrows.

Fig. 3 is a view in perspective of a stub shaft that is mounted in the body of the press and illustrating to advantage the actuating pawl which is keyed thereto.

In the drawings, numerals 10 and 11 designate skids upon which the other elements 80 of the press are mounted. The skids are connected at certain points throughout their longitudinal extent by lateral joists 12, the latter being preferably formed of a strong and durable material inasmuch as they support, to a great extent the body portion of the device. In the formation of the floor structure of the press a plurality of planks 85 or other supporting elements 13 are positioned on the joists 12, the same being approximately the same length as the skids 10 and 11 and may be formed of any suitable material, as wood or metal.

Sideboards 14 and 15 are mounted intermediate the ends of the floor structure, upon suitable standard 16, the upper ends of the sideboards being bridged by a cover 17. The cover 17 has an opening 18 formed at 100 a suitable point about which is mounted a hopper 19 to facilitate the placing of the material to be baled between the respective sideboards. In practical use it will be of course necessary to reinforce the sideboards 105 and the cover to some extent in order that

they may be made capable of withstanding the pressure exerted thereon during the baling operation. The type of reinforcing means used may be in the form of brace rods 20 such as shown in the drawing.

Posts 21 and 22 are positioned adjacent the ends of the floor structure, as shown in Fig. 1, which are connected with the sideboards 14 and 15 by spaced beams 23 and 10 24, while cross heads 25 connect the upper ends of the posts 22 and, incidentally, are connected with the cover 17 through the medium of the cover strips 26. On the other hand the upper ones of the beams 23 are 15 connected, adjacent their outer ends, by a cross head 27, the latter being reinforced through the medium of brace rods 28. Suitable cover elements also connect the cover 17 and the cross head 27.

20 Adjacent its one end, the floor structure 13 hingedly supports a door 29, as at 30, which, when in a closed position is designed to close adjacent end of the press structure, between the posts 21, yet when in an open 25 position will permit the ready removal of the bale. Any suitable means may be employed to retain the door 29 in a closed position.

30 A plunger head 31 is mounted to operate between the sideboards 14 and 15, it being of a size and shape to fit snugly between the said sideboards and between the floor structure and the cover 17. A plunger-beam 32 is carried by the said plunger head, through 35 the medium of brackets 33, the said shaft being provided with a series of ratchet teeth 34 throughout a portion of its extent whereby it may be actuated in the manner presently set forth. To more securely support 40 the plunger-beam 32 and at the same time to provide for the free and easy movement thereof, certain of the beams 24 are provided with a cross arm 35, whose stirrup portion 36 receives the shaft in the manner clearly 45 shown in Fig. 2. The provision of this cross arm also assures the retainment of the plunger-beam 32 in an approximately true horizontal plane at all times which will of course materially add to the smoothness of 50 operation of the plunger head 31.

55 In order to retain the plunger head normally in a position to permit the insertion of material to be baled between the sideboards, through the hopper 19, I provide means in the form of a retractile spring 37, one end of which has connection with one of the posts 22 as at 38, while its other end is connected as at 39 to one of the brackets 33.

60 A shaft 40 is journaled through certain of the beams 24, in proximity to the plunger-beam 32, the same having an actuating pawl 41 fixed thereto for engagement with the teeth 34 of the plunger-beam. One of the ends of this shaft 40 may be squared as

at 42, to which is connected one end of an 65 arm 43. The other end of the arm 43 has connection with a member 44 which also connects with the operating lever 45; the latter being pivotally mounted with respect to the press structure as shown at 46. Therefore, it will be seen that by drawing the operating lever 45 toward the adjacent end of the press, the arm 43 will be rocked in a manner to actuate the shaft 40 and cause the pawl 41 to engage with the teeth 34 of 70 75 the plunger beam 32 to move the plunger head 31 between the sideboards. It will also be recognized that after releasing the operating lever 45 the spring 37 will tend to draw the plunger head to its normal position. 80

A finger 47 is pivotally mounted as at 48 and carries a stud 49 adjacent one end that normally bears against the arm 43, while an extension 50 thereof has connection with one 85 end of a member 51 by which it may be actuated. The other end of the member 51 has connection with one arm 52 of a bell crank lever or treadle that is pivotally mounted as at 53, the other arm of the said lever being provided with a foot engaging portion 54. Upon movement of the arm 43 during a pressing stroke of the plunger head 31 the finger 47 will be rocked upon its pivot, by reason of the engagement of the 90 arm with the stud 49, which movement will tend to raise the foot engaging portion 54 of the bell crank lever. Consequently at the termination of the pressing stroke of the plunger head 31 the operator may, by exerting a pressure on the foot engaging portion 54 of the bell crank lever, cause the 95 arm 43 to be moved to its normal position which will carry with it the actuating pawl 41 and thus permit the free actuation of the 100 plunger head 31 and the plunger-beam 32 by the spring 37.

To retain the plunger head 39 in pressing engagement with the material to be baled at any time the operator so desires, for instance at the time of the final stroke of the plunger head, I provide a slide catch 55 that may be moved into a position to engage certain of the ratchet teeth 34 of the plunger-beam 32. This side catch may be mounted 110 with respect to the press structure through the medium of brackets 56 such as will permit movement thereof when desired.

The material to be baled is deposited between the sideboards 14 and 15 through the 120 medium of the hopper 19 and will be forced by action of the plunger head 31 toward the door 29. As more material is placed between the side-boards that which has been first placed in the press will be forced 125 against the door 29 so that the completed bale will lie between the door 29 and the adjacent ends of the sideboards 14 and 15.

After the completion of the bale, by tying the same in the usual manner the door 29 may be moved into an open position to permit the same to be easily and quickly 5 moved from the press.

From the foregoing it is believed that the advantages and novel features of my invention will be readily understood and therefore further detailed description is deemed 10 unnecessary.

In reducing my invention to practice I find that the form referred to herein as the most practical and preferred embodiment is the most efficient, but realizing that certain 15 conditions will necessarily vary in concurrence with the adoption of my device, I desire to emphasize the fact that various minor changes in the details of construction and in the proportions of parts may 20 be resorted to when required without sacrificing any of the advantages of my invention as defined in the appended claims.

Having thus fully described my invention, what I claim as new and desire to 25 secure by Letters Patent is:—

1. In a baling press, a structure to receive the material to be baled, a plunger mounted to operate in said structure, means to thrust said plunger in one direction, automatic means to return said plunger to its 30 normal position, and a treadle to return said plunger-operating means to their normal position.

2. In a baling press of the character described, a structure to receive the material to be baled, a plunger mounted to operate in said structure, means including a hand lever to impart a thrusting movement to said plunger, a spring to return said plunger to its normal position, a treadle and 40 means operable by said treadle to return

said plunger-thrusting means to their normal position.

3. In a baling press the combination of a structure to receive the material to be baled, 45 a plunger mounted to operate in said structure, a plunger-beam having teeth thereon and connected to said plunger, means to support said plunger-beam intermediate of its ends, a hand lever, means operable by 50 said hand lever to engage with the teeth of said plunger-beam and thereby impart a thrusting movement to said plunger, means to return said plunger to its normal 55 position, a treadle to return said plunger-thrusting means to the normal position thereof and means independent of said plunger-thrusting means and mounted to be moved into a position to retain said plunger against return movement. 60

4. In a baling press, the combination of a structure to receive the material to be baled, a plunger mounted to operate in said structure, a plunger-beam fixed adjacent one end to said plunger and having a plurality 65 of teeth thereon, a pawl mounted to engage said teeth, an arm to move said pawl and thereby impart a thrusting movement to said plunger, an operating lever arranged on said structure, means connecting said operating lever and said arm whereby said operating lever and said arm may be moved, means to return said arm to its normal position, and means having engagement with said arm to return 70 said pawl and said operating lever to their 75 normal position.

In testimony whereof I affix my signature in presence of two witnesses.

JESSE J. STEWART.
